UNITED STATES PATENT OFFICE.

GIUSEPPE NIGRA, OF TURIN, ITALY, ASSIGNOR TO O. M. I. M. OFFICINA MECCANICA INDUSTRIAL MAGLIERIA, OF TURIN, ITALY.

LOOP WHEEL OF CIRCULAR-KNITTING FRAMES.

Application filed December 10, 1924. Serial No. 755,007.

This invention relates to circular knitting frames with nonradial loop wheels.

By the use of loop wheels having the axis placed at an angle to the corresponding radius of the frame, difficulty has been found in so arranging that the sinkers during the revolution of the loop wheel will successively move down between two adjacent needles to operate the thread without touching the needles at any point and without causing any friction that might injure the thread.

In other words, the several members must be so arranged that while the sinkers are successively caused by the cam to move down between two adjacent needles, they will substantially be placed parallel to the latter and at equal distances apart therefrom. The term "substantially parallel" is used because the needles in fact are radial, i. e. not parallel to each other.

The requirement above referred to may be obtained in two different ways:

(1) By arranging the needles upon the rotary plate or drum of the frame at an angle with respect to the radii of said drum, and by so arranging the sinkers in the loop wheel as to form a sort of cylinder or truncated cone, say, by placing them in planes passing through the axis of the loop wheel.

(2) By keeping the needles radial upon the frame, as in usual frames, and by suitably inclining the sinkers in the loop wheel with respect to the generating lines of the loop wheel itself.

The invention has for its object an embodiment of loop wheel according to the last mentioned system.

Loop wheels according to the invention substantially consist, as described in the co-pending patent application Serial No. 740,090, filed Sept. 26, 1924, for "improvements in the loop wheels of circular knitting frames", of a guide plate or disc and a notched disc or comb, both turning synchronously with the loop wheel shaft, and carrying the sinkers therewith. According to the present invention the sinkers are no longer in planes passing through the axis of rotation, but they are in planes inclined with respect to the latter, and said planes cross therefore the faces of the guide plate and comb, which are parallel to each other, at an angle other than a right angle.

The invention is illustrated in the accom-

panying drawing, in which Figure 1 is a horizontal view and Figure 2 a vertical rear view of a loop wheel as applied to a circular frame.

The frame, which is shown for explanatory purposes only, and forms no part of the invention, comprises a vertical shaft 1 (Figure 2) supporting by means of radial arms 2, preferably flanged as at 2', a fixed platform 3. A bracket 22, suitably attached thereto, carries by its vertical depending arm 23 one of the ends of the loop wheel shaft 13, the opposite end thereof being suitably supported at 24 by means of another depending arm (not illustrated) from the said platform.

4 is the rotary plate or drum of the frame, the needles 5 being radially arranged upon, and projecting from around, the edge thereof. In Figure 2 the needles are shown by 70 a horizontal dotted line.

4 is the rotary plate or drum of the frame, the needles 5 being radially arranged upon, and projecting from around, the edge thereof. In Figure 2 the needles are shown by 70 a horizontal dotted line.

A toothed driving wheel 14 is suitably fixed to the loop wheel shaft 13, near its inner end, said wheel 14 meshing with a circular rack 15 on the upper face of the rotary plate or drum of the frame, to drive the loop wheel. The latter comprises the notched disc or comb 17 and the guide plate 18, which control the up and down movements of the sinkers 16, as described in the previous specification above mentioned. 20 and 21 are the positioning springs, as described in the co-pending patent application Serial No. 740,091, filed September 26, 1924, for "improvements in the loop wheels of circular knitting frames" 25 are the knocking over platines vertically arranged around the drum 4 and adapted to knock down the loops from the needles over the thread to form the stitches.

As shown in Fig. 2, the sinkers, consisting as usual of small sheet metal plates, are not in planes passing through the axis of rotation of the loop wheel, but in planes inclined with respect to the said axis. For instance, 100 A B shows the trace of the plane of one sinker over the plane C D (Figure 1) tangential to the tails of the sinkers.

The inclination of such planes with respect to the faces of either guide plate and comb is substantially as shown in Figure 1, wherein the references 16^a, 16^b . . . 16^e denote the traces of the planes of the five lowermost sinkers over the horizontal needle plane 5 (Figure 2).

In order to comply with such inclination and to maintain the sinkers in their normal positions during their rocking movement, the comb should necessarily be provided with 5 correspondingly inclined notches, and the grooves in the front edge of guide plate should be similarly inclined to guide the tails of the sinkers. The angle of inclination of the traces 16 (Figure 2), say the 10 radius of the circle, which the several traces A B are tangential to, is so determined that the sinkers, which in turn move down between two adjacent needles, will substantially be in the middle plane thereof. 15 As an illustration, it may be stated that for given sizes of frame and loop wheel, and for a given inclination of the axis X Y (Figure 1) with respect to the needles in the frame drum, it has been found advisable to make the planes of the sinkers cross the axis of rotation of the loop wheel at M, say where the said axis crosses the middle 20 plane L N of the comb edge. This indication is given by way of example only, as it 25 will easily be understood that the crossing point referred to will vary when any of the mentioned conditions are modified.

What I claim as my invention is:—

1. In a knitting machine of the type described, a loop wheel comprising a comb, a 30 guide disk spaced from the comb and parallel therewith, and rocking sinkers mounted in the comb and having their tails engaging the guide disk at a point at one side of a point directly opposite the connection of 35 the sinkers with the comb, whereby the sinkers will extend diagonally across the comb and guide disk and lie in planes inclined to the axis of the loop wheel.

2. In a knitting machine of the type described, a loop wheel comprising a comb having notches inclined to its axis, a guide disk spaced from the comb and parallel therewith, and rocking sinkers mounted in the notches of the comb and having their 40 tails provided with notches engaging the periphery of the guide disk, whereby the sinkers will extend diagonally across the comb and guide disk and lie in planes inclined to the axis of the loop wheel. 45

In witness whereof, I have hereunto signed my name.

GIUSEPPE NIGRA.
